UNITED STATES PATENT OFFICE.

EDWARD W. N. BOOSEY, OF DETROIT, MICHIGAN.

CLEAN-OUT FITTING FOR PLUMBING SYSTEMS.

Application filed November 26, 1926. Serial No. 150,756.

This invention relates to a cleanout fitting for waste systems in plumbing installations and is of the nature of a ferrule adapted at its lower end for attachment in such systems and the upper end of which is substantially flush with the floor line and formed with a removable cap permitting access to the interior thereof.

An object of the invention is to provide a fitting of the type stated normally of a length greater than is necessary for the position it is to occupy and having its walls provided with circumferential grooves both interiorly and exteriorly permitting it to readily cut to proper length after installation, practically flush with the floor line for instance, and a removable cap member is provided adapted to be supported in the interior of the end thereof under which condition the internal grooves provide a retaining means for the packing by means of which the cap member is sealed to the fitting. The fitting may also be provided with an inlet for the direct connection of a conduit thereto or such inlet may be dispensed with depending upon the requirements of the installation.

These and other objects and the several novel features of the invention are herein-after more fully described and claimed, and the preferred form of construction of a device embodying my invention is shown in the accompanying drawings in which—

Fig. 1 is a vertical section of my improved cleanout fitting applied to a drainage fitting.

Fig. 2 is an elevation showing a plumbing system in which two fittings embodying my invention are utilized, the floor being indicated in section.

The fitting is in the form of a cylindrical member 1 or 2 indicated in Fig. 2 and has a closed upper end 3 provided with a wrench-hold 4 and its lower end is threaded, as will be understood from Figs. 1 and 2, for threaded relation with a portion of the plumbing system as indicated at 5 and 6 for the members 1 and 2 respectively.

The plumbing system here shown forms no part of the present invention and is shown merely as illustrative of the use to which the invention may be put.

In the construction of a building the plumbing is installed before the building is finished and this cleanout fitting is applied at the time the plumbing is installed and is of a length to extend above the possible finished floor line indicated at 7 and both the

exterior and interior wall surface of the fitting are circumferentially grooved as indicated at 8 and 9 in Fig. 1. These grooves weaken the wall of the fitting, it being formed preferably of cast iron and may be cut by means of a hammer and chisel so that the upper end of the fitting lies very close to the floor surface 7. The fitting is provided with the closed end 3 so that waste material, such as shavings, plaster and the usual waste material that arises in the construction of a building, is prevented from passing into the fitting and therefore into the plumbing system and the wrenchhold 4 is provided on this closed end to enable the fitting to be screwed into the plumbing fixture with which it is associated. Subsequent to the finishing of the building and of the floor surface the projecting closed end of the fitting is severed from the body by means of a hammer and chisel to a point approximately on a plane with the floor surface and a cylindrical member 10 of less diameter than the fitting is inserted in the top. The member 10 is provided with a lateral flange 11 at its lower end of a diameter closely approximating the internal diameter of the fitting 1 or 2 and the space between the outer wall of the member 10 and the inner wall of the fitting is filled with the packing 12 of any desired type. The member 10 is internally threaded at its upper end for the reception of a cap 13 which is flanged as indicated at 14 to extend over the upper end of the fitting and providing a neat looking finished end therefor and covers the severed end of the fitting which is more or less unsightly due to its having been cut with a chisel. This cap 13 is preferably formed with an external recess 15 by means of which it may be screwed in place with a wrench or the periphery thereof may be formed in the shape of a nut. The internal grooves it will be noted become filled with the lead or other packing that is utilized in supporting the member 10 and a tight joint is provided between the member 10 and the fitting which prevents an escape of gas. The threaded cap is preferably provided with a shoulder 16 engaging the upper end of the ring 10 to form a tight seal.

In Fig. 1 I have shown the fitting at 1 as supplied with a threaded inlet 17 and in Fig. 2 the fitting at 2 is shown without such inlet. Preferably the walls of the fitting, whether it is in the form shown at 1 or at 2 in Fig. 2, are thickened as indicated at 18 in Fig. 1,

this part of the structure being subject to the greatest strain in assembling the fitting with a conduit.

From the foregoing description it is evident that the device is of simple form; is readily assembled in its original form in a plumbing system, and the invention comprises the fitting with the closed end and its construction and arrangement permitting cutting to length and association of the member 10 and cap subsequent to assembly of the fitting in a plumbing installation.

Having thus briefly described my invention, what I claim and desire to secure by Letters Patent of the United States is—

1. A cleanout fitting for plumbing installations comprising a hollow cylindrical member having a threaded open end and means for closing the opposite end providing a wrench-hold for threading the device to a conduit, said fitting having a hub adjacent the threaded end for connection of a conduit therewith, the wall of the fitting being internally and externally circumferentially grooved providing a series of weakened areas permitting severance of the closed end thereof at any of a number of points, the internal grooves being in staggered relation with the external grooves.

2. A cleanout fitting for plumbing installations comprising a hollow cylindrical member having a threaded open end and means for closing the opposite end providing a wrench-hold for threading the device to a conduit, said fitting having a hub adjacent the threaded end for connection of a conduit therewith, the wall of the fitting being internally and externally circumferentially grooved providing a series of weakened areas permitting severance of the closed end thereof at any of a number of points, the internal grooves being in staggered relation with the external grooves, said means for closing the said opposite end comprising an open ended

cylindrical member less in external diameter than the internal diameter of the fitting and having a flange at its inner end of a diameter approximately equal to that of the internal diameter of the fitting and being internally threaded at the opposite end, a packing between the cylindrical member and the grooved interior of the fitting above the flange, the grooves providing a means tending to retain the packing in place, and a closure for said cylindrical member comprising a cap having a portion threaded for engagement with the threaded end of the cylindrical member, and a lateral flange there-beyond covering the end of the fitting.

3. A cleanout fitting for plumbing installations comprising a hollow cylindrical member having an externally threaded open end, the wall of the fitting at the threaded end being of greater thickness than the comparatively thin remaining portion, the said remaining portion being formed with a series of circumferential grooves in both the exterior and interior surface providing weakened areas permitting ready severance thereof to provide a fitting of the desired length, the interior grooves being in staggered relation with the exterior grooves, a hub formed integrally with the wall of the fitting adjacent the portion of greatest thickness of wall providing for attachment of a conduit, and a closure member for the opposite end of the fitting comprising a ring like portion internally threaded at its upper end and a packing between the member and the inner grooved face of the fitting providing a construction in which the packing fills the grooves and thereby prevents ready withdrawal of the ring member, and a cap in threaded relation with the ring.

In testimony whereof I sign this specification.

EDWARD W. N. BOOSEY.
